UNITED STATES PATENT OFFICE.

THOMAS M. TAGGART, OF BELVEDERE, CALIFORNIA.

GASIFIER FOR LOW-GRAVITY OILS.

1,392,463.

Specification of Letters Patent.

Patented Oct. 4, 1921.

Application filed February 7, 1920. Serial No. 357,056.

To all whom it may concern:

Be it known that I, THOMAS M. TAGGART, a citizen of the United States, and a resident of Belvedere, Marin county, California,

5 have invented new and useful Improvements in Gasifiers for Low-Gravity Oils, of which the following is a specification.

My invention has for its principal object means whereby low gravity oils may be 10 readily ignited, as for use in burners. A further object of my invention is to provide an indestructible gasifier. These objects I accomplish by supporting a small quantity of the oil in a receptacle having very thin 15 metal walls, and having an air exposed surface such that when a flame is applied to the edge of the receptacle the heat is not withdrawn from the oil to any material degree and is available for gasifying the oil 20 film adjacent to the receptacle wall and the flame, to a sufficient degree to support combustion. The flame is then immediately transmitted over the balance of the receptacle exposed surface thus establishing ignition 25 of the fuel oil.

Where the fuel oil is to be gasified from a well at the bottom of the burner area I locate the gasifier at a point where it either receives the fuel direct from a fuel conveying tube, or, the gasifier may be partially 30 immersed in the fuel in a well, such that a portion of the fuel will run into the gasifier compartment, or the gasifier may be filled with infusorial earth, or similar material, 35 and the oil may be readily ignited from its surface in the manner described, or the gasifier may be raised within the burner to an exposed position so that it may be readily reached by a flame from the top of the 40 burner and thus ignited; or, pilot lights may be arranged adjacent to the gasifier in its depressed or any other convenient position.

By referring to the accompanying drawings my invention will be made clear.

45 Figure 1 is a plan view of a burner fitted with my gasifier.

Fig. 2 is a cross section of Fig. 1 on the section line II—II.

Fig. 3 is an enlarged section through a 50 burner well and gasifier of Fig. 2.

Fig. 4 is an enlarged section through the well and gasifier and a portion of the burner similar to Fig. 1, but employing different means of mounting the gasifier and showing 55 inert capillary material mounted therein serving as an absorbent.

Fig. 5 is a cross section partly diagrammatic showing another means of feeding the fuel oil to the gasifier and also showing pilot burners to ignite the fuel at the gasifier.

Throughout the figures similar numerals refer to identical parts.

The numeral 1 indicates the well within which the fuel oil is gasified, the said oil 65 being fed through the supply connection 2 and rising in gasifier 3, which in the figures is shown of annular form. The gasifier 3 is supported within the well 1, and preferably above any normal oil surface therein 70 by rods as 4, 4 which may conveniently be adapted to pass through openings in the wall as 5. These latter may be supported from the frame 6, preferably having a central rod 7, such that raising the central rod 75 as by the finger member 8 will raise the gasifier 3 to the top 9 of the burner 10. This gasifier 3 is to be made of very thin metal, and I prefer to use a metal thickness of about #34 U. S. standard gage, or thinner, but good results may be obtained with a thickness as great as #22, and in any event the metal thickness must be such that the heat conductivity of the body of the metal will not be such as to cause rapid 80 heat abstraction from the igniting flame. 85

The fuel in the gasifier may then be readily ignited and the gasifier lowered into the position of Fig. 2, when it will ignite the gas in the burner 10 from the fuel which 90 is now being gasified from the well 1.

In the alternate construction, as indicated in Fig. 4, the gasifier 3 is filled with infusorial earth or other porous inert material, preferably molded therein, and which through capillary action absorbs the oil as from the well 1 and thus exposes an inflammable oil surface on the upper part as 11, which may now be ignited in the manner previously described.

100 Or the gasifier, either of the type indicated in Fig. 3 or Fig. 4, may be mounted either on the supporting wires 4 or on the cross bars 12, and by utilizing a pilot burner, or burners, as indicated at 15 in Fig. 5, will 105 form the igniting means for the burner. After ignition, the flame from the fuel burns within the space 10, combustion being supported therein by air as through the holes 13, 14.

I claim:

1. In a burner a gasifier for low gravity

liquid fuel formed of thin metal and of annular form and supported from below an annular chamber formed about a central axis and within which said gasifier is disposed and through which it may be raised, means extending through the bottom of said chamber and supporting said gasifier and a central member extending upward substantially at the chamber axis and adapted to 5 operate said supporting means from above the burner to raise and lower said gasifier in said chamber.

2. In combination a gasifier and a burner as set forth in claim 1 wherein there are a plurality of members below the gasifier to 15 hold it spaced from the bottom of said chamber and wherein the bottom of said chamber is constructed and adapted to contain fuel adapted to be ignited by said gasifier.

In testimony whereof, I have hereunto set 20 my hand at San Francisco, California, this 30 day of January, 1920.

THOMAS M. TAGGART.
